UNITED STATES PATENT OFFICE.

CHARLES FRANCIS JENKINS, OF WASHINGTON, DISTRICT OF COLUMBIA.

DESIGN FOR A GAITER.

60,683.

Specification for Design.

Patented Mar. 21, 1922.

Application filed July 21, 1921. Serial No. 486,605. Term of patent 3½ years.

To all whom it may concern:

Be it known that I, CHARLES FRANCIS JENKINS, a citizen of the United States, and resident of Washington, in the District of Columbia, have invented a new, original, and ornamental Design for Gaiters, of which the following is a specification, reference being had therein to the accompanying drawing.

The drawing shows in perspective view a gaiter formed in accordance with my design, in which parts corresponding to the vamp and quarters of a shoe are of one piece divided at one side, near the instep, overlapped, and connected by buttons. Near and below the overlapping, a strap passes downwardly and toward the opposite side of the

gaiter, and from the rear portion of the quarters a divided button-secured strap passes obliquely upward and forward from side to side of the gaiter, forming an instep loop.

The gaiter as a whole is adapted to cover and conceal the upper margins of the vamp and quarters of a shoe, and its own margins are gracefully curved to harmonize with curves of a shoe with which it may be worn.

What I claim is:

The ornamental design for a gaiter as shown and described.

In testimony whereof I hereunto affix my signature.

CHARLES FRANCIS JENKINS.
